ROAD SURFACING MACHINE

Karl E. Kramer, Oelrichs, S. Dak.

Application November 7, 1933, Serial No. 696,970

5 Claims. (Cl. 37—108)

This invention relates to road surfacing machines, its primary object being to provide a machine of simple construction which when pulled or otherwise impelled over the surface of a road, smooths the same by the elimination of depressions and by removal of projections.

The machine is particularly adapted to even the surface of a road which, by heavy travel or other causes, has been transversely corrugated, or on which by constant wear parts of the foundation or bed-rock have been exposed.

In the operation of the machine these corrugations which destroy the surface of the road to what is commonly known as a corduroy or washboard condition are cut down and filled, while protruding rocks are chipped off to the desired level.

It is a further object of the invention to produce the above stated results by means of a vehicle supported on runners or crawler tracks to move evenly along the road to be planed, without undue upward or downward displacement, and which carries a cutting and breaking element in the form of a series of pivoted and weighted chisels mounted for rotation about a common axis.

Another object of the invention resides in the provision of means by which matter loosened by the action of the cutting and breaking element is evenly distributed over the surface of the road, and still further objects reside in details of construction and in novel and advantageous arrangements and combinations of parts, as will be fully brought out in the course of the following description.

In the accompanying drawings, in the several views of which like parts are similarly designated,

Figure 1 is a partially sectional side elevation of a road surfacing machine embodying the distinctive features of the invention,

Figure 2 is a transverse section along the line 2—2 of Figure 1,

Figure 3 is a fragmentary section taken on the line 3—3 of Figure 1,

Figure 4 is an end view of the lower portion of the vehicle looking in the direction of the arrows 4—4 in Figure 1,

Figure 5 is an enlarged sectional view of the working portion of one of the chisels included in the cutting element of the machine,

Figure 6 is a side elevation of the machine, drawn to a smaller scale, showing the substitution of endless chains for the runners of the construction illustrated in Figure 1,

Figure 7 is an end view of the machine shown

in Figure 6, looking in the direction of the arrows 7—7.

Figure 8 is a diagrammatic view illustrating the action of the cutting element in the operation of the machine, and

Figure 9, a fragmentary side view, looking in the direction of the arrows 9—9 in Figure 2.

Referring first to Figures 1 and 2 of the drawings, the machine comprises a sled composed of parallel runners 5, preferably made of channel bars, suitably connected as by channelled cross bars 6. Mounted upon the runners at the forward end of the vehicle are standards 7 for bearings in which the cutting element of the machine is mounted.

The bearings are adjustable with relation to their standards so that the cutting element may be adjusted to conform with varying requirements in the operation of the machine.

The cutting element comprises a shaft 9 mounted for rotation in the bearings and provided with a series of collars 10 having radial, slotted lugs 12 and fixed on the shaft by pins 13 or other suitable fastening means.

Pivoted in the slotted lugs by means of pins 14 are cutting members 15 in the form of weighted chisels or hammers, the outer extremities of which are enlarged to provide heads 16 which during rotation of the shaft greatly increase by their impetus the force with which the cutting members act upon the work.

The heads of the hammers are recessed to receive tips 17 of case hardened chromo vanadium steel which constitute the bits of the chisels, which in the operation cut into the unevennesses or projections on the road surface.

The tips 17 are fastened to the hammer heads by bolts 18 so that they are readily removed in case of wear or breakage.

The cutting element is adjusted so that the ends of their arms move in a circle extending a short distance below the plane of the road-engaging lower surfaces of the runners.

The shaft of the cutting element is rotated by connection with an engine 19 mounted upon a support at the rear or tail end of the vehicle, and it is a distinctive feature of the invention that the direction of rotation of the cutting element, indicated by the arrows 20, is the same as the direction in which the vehicle moves along the road as indicated by the arrow 21. The connection between the rotary cutting element and the motor may be established by means of pulleys 22 and 23, and a belt 24.

It is to be understood, however, that if prac-

tical the cutting or breaking element may be operated from a tractor used to pull the vehicle along the road.

A suitable clevis or apertured lug 25 is mounted 5 at the forward end of the vehicle to attach a tow chain or other means by which the sled is connected to the tractor.

A housing 26 which is open at its bottom encloses the cutting or breaking element and projects rearwardly thereof. The housing is pivotally supported upon the runners at their rear ends as at 27, and screw bolts 28 in apertured lugs 29 on the sides of the housing at the forward end of the same engage in threaded apertures of the runners in order to vary the elevation of the housing above the surface of the road by movement about its pivots.

At the forward end of the housing is a hinged apron 30 which rides over the surface of the road, 20 and around the bearings of the cutting element are openings 31 for the admission of air to the interior of the housing.

The lower edges of the sides of the housing slant upwardly toward the rear end of the vehicle 25 to provide a space 32 for the passage of loosened matter, and the housing tapers toward its rear end in order to direct said matter to said space.

In the operation of the machine, the cutting and breaking element is rotated in the direction 30 of the arrows 20 at a high velocity of approximately 1500 revolutions per minute, thereby causing the weighted chisels to engage the surface of the road, three times per inch when the machine moves at a speed of three miles per hour.

35 The violent impact of the cutting edges of the rotating chisels, augmented by centrifugal force owing to their pivotal connections with the collars 10 on the shaft cuts down the ridges or corrugations, such as shown at 33 in Figure 8, and fills 40 the hollows between the ridges, and in case a protruding rock or stone is encountered as indicated at 34, the sharp cutting edges of the chisels will remove the projecting portion thereof by a chipping action until it is level with the surface 45 of the road.

Under most conditions it is desirable that the cutting element be rotated in the same direction in which the vehicle is moved along the road, so that the cutting edges of the chisels engage the 50 obstructions to be removed in a forwardly and upwardly directed movement and by a chipping action without the obstructive resistance which would be encountered if the element were rotated in the opposite direction.

55 In addition to the above named advantages, the rotary movement of the cutting element in the direction of the movement of the vehicle greatly increases the effect of the cutting action and lessens wear on the cutting bits of the hammers.

60 The use of runners is also of more than ordinary importance, since it permits of the vehicle remaining on a level with the surface of the road instead of moving up or downwardly when encountering obstructions in the road as would be the case if the vehicle were supported by wheels.

65 In this connection, it is to be understood that in leveling a road surface, the vehicle moves first along an edge of the road where the surface is usually smooth and not roughened by travel, while subsequently it moves over leveled portions of the road surface, so that the runners constantly engage with a level part of the road and thereby maintain the vehicle on an even keel throughout the operation.

70 75 The rapid rotary movement of the cutting or

breaking element causes air to be drawn into the housing through the openings 31, in currents directed downwardly to the surface of the road and to and through the space 32 at the rear end of the machine. The air currents distribute the matter loosened by the cutting element evenly over the surface of the road, so that under ordinary conditions no further operation is required to bring the surface to a smooth and even condition. The apron 30 closes the front of the housing to prevent the escape of air at that point, while its hinged connection permits its movement across unevennesses or obstruction on the road.

10 A hinged door 35 at the top of the housing affords access to its interior.

15 In the modified construction, illustrated in Figures 6 and 7 of the drawings, endless track chains 36 supported on wheels 37 are substituted for the runners 5 of the vehicle shown in Figure 1.

20 The crawler tracks thus provided are of particular value where the machine is used in surfacing exceptionally rough roads, otherwise the operation of the machine is the same as hereinbefore described.

25 Having thus described my road surfacing machine, it is to be understood that variations in details of construction and the arrangement of the elements and parts comprised therein may be made without departure from the spirit and scope 30 of the invention.

What I claim and desire to secure by Letters Patent is:

1. A road surfacing machine comprising a 35 housing supported for its movement over the surface of a road in a given direction, the housing being closed at its forward end with relation to said direction of movement, and being spaced from the surface of the road at its opposite end, and a rotary cutting element in the housing engaging with the surface of the road, the housing having an opening for the intake of air by rotation of the element.

40 2. A road surfacing machine comprising a 45 housing supported for its movement over the surface of a road in a given direction, the housing being closed at its forward end with relation to said direction of movement, and being spaced from the surface of the road at its opposite end, and a rotary cutting element in the housing engaging with the surface of the road, the housing having an opening for the intake of air by rotation of the element, and the housing tapering rearwardly to direct currents of in-drawn air to 50 and through the space at its rear end.

55 3. A road surfacing machine comprising a 60 housing supported for its movement over the surface of a road in a given direction, the housing having at its forward end, with relation to said direction of movement, a hinged apron closing the housing at said end by engagement with the surface of the road, and the housing being spaced from the surface of the road at its opposite end, and a rotary cutting element in the housing engaging with the surface of the road, the housing having an opening for the intake of air by rotation of the element.

65 4. A road surfacing machine comprising a 70 housing supported for its movement over the surface of a road in a given direction, the housing being closed at its forward end with relation to said direction of movement, and being spaced from the surface of the road at its opposite end, a rotary cutting element in the housing engag- 75

ing with the surface of the road, the housing having an opening for the intake of air by rotation of the element, and means for vertical adjustment of the housing to vary the width of the space between its rear end and the surface of the road.

5. A road surfacing machine comprising a housing supported for its movement over the surface of a road in a given direction, the housing being closed at its forward end with relation to

said direction of movement, and being spaced from the surface of the road at its opposite end, and a rotary cutting element in the housing engaging with the surface of the road, the housing having an opening for the intake of air by rotation of the element, and the housing being adjustable to vary the width of the space between its rear end and the surface of the road.
